(57) **CLAIM**

The ornamental design for a sign, as shown and described.

DESCRIPTION

FIG. 1 is an exploded perspective view of the present invention;

FIG. 2 is a front elevational view of the present invention;
FIG. 3 is a right side elevational view of the present invention, the left side elevational view being a mirror image thereof;

FIG. 4 is a top plan view of the present invention;

FIG. 5 is a bottom plan view of the present invention; and,
FIG. 6 is a fragmentary rear view of the present invention showing the bottom portion, the top portion being identical to FIG. 2.

The broken lines in FIGS. 1, 2 & 5 represent fold lines and form part of the claimed design.

1 Claim, 2 Drawing Sheets

FIG. 6.

FIG. 1.

FIG. 2.FIG. 3.FIG. 4.FIG. 5.
